UNITED STATES PATENT OFFICE.

EARL R. MOODY, OF CHESTER, PENNSYLVANIA.

FENDER MECHANISM.

1,269,488.

Specification of Letters Patent. Patented June 11, 1918.

Application filed March 15, 1918. Serial No. 222,758.

To all whom it may concern:

Be it known that I, EARL R. MOODY, a citizen of the United States, residing at Chester, in the county of Delaware and State of Pennsylvania, have invented certain new and useful Improvements in Fender Mechanism, of which the following is a specification.

This invention relates to fender mechanism which is principally designed for use on self-propelled vehicles although the principles may be utilized generally for the front fenders of moving bodies.

My main object is to provide a fender which is collapsible to fold around a person, cattle or other objects which it may strike during travel of the vehicle to which it is attached, in combination with a net or receiving structure into which the "captive" may fall and be saved from injury.

Serviently, I aim to devise the various features of construction, arrangement, and combination of the parts, as will be minutely described hereinafter, with reference to accompanying drawings, showing one preferred embodiment, and among which objects may be briefly mentioned:—pivoted arms with a spring-controlled means to normally maintain them spread; with means to automatically lock them through engagement with an object; with fender sections (preferably padded) to directly strike the object and fold inwardly; with a net means having a frame operable through movement of the said arms to move the net proper to attaching position, and a spring-controlled means to normally retract the net.

In the drawings:

Fig. 1 is a plan view showing my improved fender mechanism associated with the front of an automobile;

Fig. 2 is a view of the parts of Fig. 1 in vertical central section;

Fig. 3 is a detail perspective view of the net-extending frame;

Fig. 4 is a fragmentary vertical sectional view through the net casing and spring-controlled roller mechanism;

Fig. 5 is a cross sectional view on the line 5—5 of Fig. 4;

Fig. 6 is a view mostly in vertical section, of the means for pivotally mounting the fender arms and driving the suspending means of the net;

Fig. 7 is a side elevation of the means for

mounting the fender arms taken at a different angle to Fig. 6;

Fig. 8 is a plan view of the means for mounting the fender arms and driving the net-extending means;

Fig. 9 is a detail side elevation of one of the gear members used in connection with the net-extending means;

Fig. 10 is an enlarged, fragmentary view, showing the fender proper in top or plan, and

Fig. 11 is a front elevation of the parts of Fig. 10.

Referring specifically to the drawings, the fender proper is provided at A, being made preferably in a plurality of collapsible sections, as will be later specifically described and being carried and mounted by angularly disposed arms 12 which swing inwardly from pivots of attaching and mounting devices B.

Each attaching and mounting device B preferably comprises two sections, namely a stationary section 13 and a movable section 14. These sections have overlapping flanges at 15. In any suitable manner, as by means of U-bolts 16, passing through lateral extensions or lugs 17 of section 13, the devices B may be rigidly secured to and at the front end of the usual side beams B, as suggested at 17, of an automobile chassis. Beneath the beams 17, the arms of the bolts may pass through a clamp plate 18, and beyond said plate, the arms may receive fastening nuts 19. Rising from and centrally within the section 13 is a bolt 20 which serves as the bearing or pivot for arms 12. This bolt is secured to the bottom wall of section 13 in any desired manner, and for instance by means of the particularly shaped head 21 as shown. The bolt 20 extends loosely through the top wall of the section 14, and above it receives a fastening nut 22. Section 14, it will be realized, turns from the bolt or bearing 20 and on the section 13. Sleeves 23 radiate from the section 14, and the arms 12 are screwed into the sleeves as shown. Coil springs 24 are disposed within the sections 13 and 14, and normally urge the arms 12 toward each other and out of the position shown in Fig. 1. To this end, the spring is at opposite ends, secured to the sections 13 and 14, preferably by extending the ends into sockets 25 and 26, respectively, of said sections.

Arms 12 at their outer extremities, termi-

uate in upwardly and forwardly projecting studs 27 which have screw threads so as to detachably enter the sockets provided with screw threads in heads or blocks 28, 5 preferably ornamentally finished. Suitably fastened to the rear of each of the blocks or heads 28, are hinge leaves 29, which by means of pintles 30 are hinged to fender bars or sections 31. Sections 31 are bridged or 10 joined by a fender bar or section 32. Sections 31 and 32 are pivotally or hingedly connected together in any suitable manner as by means of the pintles 33. Outward movement of these fender sections 31 and 32, is 15 limited, by inwardly extending lugs or stops 34 provided on the sections 31 and 32 adjacent the pivots 33 and which stops abut when the fender sections are in their normal position as shown in Fig. 1.

20 The device collapses into the dotted line position shown in Fig. 1, as will be later specifically described, and the parts are automatically locked in this position by a suitable means. One form of such means is best 25 shown in Figs. 7 and 8. Referring thereto, a dog 35 is pivotally connected to the section 26 by means of a removable set screw 36. The dog at its lower end has a beveled wall 37 which cooperates with the top of one of 30 the lugs 38 so as to tilt in passing one of the lugs and then fall between the lugs into the locked position as Fig. 7 shows. The dog 35 cannot unduly tilt in the opposite direction since a bevel gear rack 39 is disposed in the 35 path of movement.

Said bevel gear rack 39 is formed integrally with and extends laterally from the movable section 26. Meshing with the teeth of the bevel gear rack 39 are segmental bevel 40 gears 40, preferably mounted from the sections 13 by means of bolts 41. Intermediate the sections 13 and the segments 40, sleeves or collars 42 are preferably disposed. Said segmental bevel gears 40 are screwed tightly 45 onto the bolts 41 of a net-extending frame. The frame is preferably made in a single piece as shown in Fig. 3. From the ends 41, this frame has downwardly and rearwardly inclined arms 42 which lead to horizontal 50 arms 43 joined by a bridge or transverse arm 44. To the bridge 44, a net 45 of any suitable width and material is connected. This net is flexible and by way of example, may be made from canvas.

55 The opposite end and surplusage of the net is wound around a roller or shaft 45 (see Figs. 2, 4 and 5) mounted in a cylinder or casing 47 and one end of which, 48, is removable to facilitate insertion and removal 60 of the parts. This end 48 may be screwed to the casing proper shown. At the bottom of the casing an opening 50 is provided through which the net 45 passes. A spiral spring 51 is fastened to shaft 45 as at 52 65 and also to the casing as at 53. This spring

is used to normally wind the shaft 45 to wrap the net around it and rewind the net after operation of the fender mechanism. In order to prevent interference between the net and the spring 51, a removable disk or 70 plate 54 may be interposed between them, surrounding the shaft 45 as shown in Fig. 4.

The casing 47 may be mounted at any desired location and from any approved part of the vehicle. However, it is preferably 75 mounted in the present instance from the front axle of the automobile, as shown in Figs. 1 and 2, by the means of U-shaped hangers or brackets. The axle is designated 55 and the hangers are designated 56. Set 80 screws or bolts 57 may clamp or fasten the hangers in place. The hangers of course are rigidly secured to the casing in any approved manner.

In order that the construction involved 85 in this invention may not be confused with the present automobile structure, I have shown the automobile structure for the most part in dot-dash lines. There will be no confusion therefore with the dotted lines 90 representing positions which my improved apparatus may take. The automobile parts of course are also merely diagrammatic and shown to enable a better understanding of the invention to be had. To this end, it 95 may be mentioned that the front wheels are shown at 58 and the propelling engine at 59.

It may be stated too that I prefer the top 100 of the fender sections 31 and 32 to be disposed at a distance of two feet and ten inches in most instances above the ground. At this height, the fender will engage an adult below the hips and a child around the waist. To minimize the impact and injury to "captive" persons, the sections 31 and 32 105 on their outer faces are preferably padded as at 60, in any approved manner.

As the automobile or other vehicle travels 110 and it strikes a person or other object, section 32 of the fender will move directly backward in the direction of the arrow to the dotted line position shown in Fig. 1. Sections 31 will move in the direction of their arrows into the dotted line position of the same figure and arms 12 will also 115 move to the dotted line position as shown in this view. Sections 31 and 32 move from the pivots 30 and 33, while the arms 12 move from the bearings 14 on flanges 15. Springs 24 are not strongly tensioned and hence the 120 apparatus will not injure the captive during movement of the fender to the dotted line position. The folded parts assume the shape substantially of a triangle and surround the person or other object. As the 125 parts described fold, the teeth of bevel gears 39, turn the bevel gears 40 and accordingly swing the frame 41-44 outwardly to the dotted line position shown in Fig. 2, moving with it of course the net 45 so that this 130

may extend under the feet of the "captive." After the parts move to the dotted line positions of Figs. 1 and 2, they automatically lock in that position by reason of the engagement of the dogs 35 intermediate the pins or lugs 38. In order to release the object or "captive," the set screws 36 are removed or loosened so that the dogs 35 may be moved from between the lugs 38. After such removal, the operator may restore the arms 12 to the position of Fig. 1 and these arms will of course move the fender sections to the usual position and the gear members 39 and 40 will restore the frame 41-44 to its normal position, while the springs 51 will rewind the net. Lugs 34 prevent collapse of the fender until it again engages an object.

I have shown merely one preferred embodiment of the invention, in view of which fact it is to be understood that I reserve the many changes in the details of construction and arrangement and combination of the parts as may be made, within the spirit and scope of the appended claims.

I claim:—

1. A fender mechanism having foldable fender sections to abut an object, and means mounting said sections and foldable there-with.

2. A fender mechanism having a plurality of fender sections to abut an object with the outermost section foldable inwardly to move the object substantially toward the center.

3. A fender mechanism having a plurality of fender sections to abut an object, one of said sections being movable rearwardly, and the remaining sections being movable inwardly relatively thereto through its rearward movement.

4. A fender mechanism having a plurality of pivotally connected sections foldable through abutment against an object, said sections having stop mechanism to limit

their extent of outward movement, means suspending the sections, means to pivotally mount said suspending means, and means associated with the second mentioned means to urge the second mentioned means to fold during folding of the sections.

5. A fender mechanism having a plurality of arms, spring means to urge folding of the arms, foldable fender sections mounted by said arms to abut an object, and means on the sections to prevent operation of the spring means until abutment with an object.

6. A fender mechanism having a plurality of arms, operating spring means for the arms, foldable fender sections, and said sections being pivoted to each other and to said arms.

7. A fender mechanism having a plurality of arms, operating springs therefor, heads on the arms, hinge leaves extending from the heads, foldable fender sections, and

means to hinge the fender sections to said leaves.

8. A fender mechanism having a collapsible fender, normally retracted means to engage an object from below and means 70 positively driven for operation simultaneously with collapse of the fender to project said normally retracted means.

9. A fender mechanism having a collapsible fender to fold around an object, and 75 means positively driven through movement initiated by the fender to engage the object in a different plane from the plane of movement of the fender.

10. A fender mechanism having an outwardly movable net, means to normally maintain the net retracted and to automatically retract the net after operation, and means to project the net acting counter to the first mentioned means. 80

11. A fender mechanism having an outwardly movable net, a frame to which the net is connected, said frame having side arms, gears secured to said side arms, means on which the gears are pivoted to mount the 90 frame, and means to drive the gears to project the net.

12. A fender mechanism having a collapsible fender, pivotal mounting means therefor, having a fixed section and a movable section, an object supporting device, a gear member associated with the device and turnably mounted from the fixed section, and a gear member meshing with the first mentioned gear member and movable with 100 the movable section.

13. A fender mechanism having a collapsible fender, pivotal mounting means therefor having a fixed section and a movable section, an object-supporting net, and 105 means mounted from said sections and positively operable by movement initiated by the movable section to project the net.

14. A fender mechanism, having a collapsible fender, pivotal mounting means 110 therefor, means to urge folding of the fender, means to normally prevent folding of the fender, a net, means to project the net through movement of the fender, and means to retract the net.

15. A fender mechanism, having a fender comprising a plurality of sections, means to limit the outward movement of the sections, pivotal mounting means for the sections having a fixed section and a movable 120 section, means to urge movement of the movable section inwardly to fold the fender sections, stop means on the fender sections, a net, gearing means operable by movement of the movable section to project the net, and 125 means to retract the net after projection.

16. A collapsible fender having a pivotal mounting means comprising a fixed section and a movable section, a bolt adjoining the sections, a spring surrounding the bolt and 130

- 1 at opposite ends being secured to the respective sections, and coöperating fastening means on the sections engageable to fasten the fender in collapsed position.
- 5 17. In fender mechanism, a plurality of collapsible fender sections, pivotal mounting means therefor, said mean having a fixed section and a movable section, a pivoted dog on one of the sections, and keeper means for the dog on the other section.
- 10 18. A collapsible fender having a pivotal mounting means comprising a plurality of sections, one of said sections being movable, a dog pivoted to said movable section, keeper means on the other section for said dog, and abutment means on the movable section for the dog to prevent undue movement in the improper direction.
- 15 19. A collapsible fender having an arm, pivotal mounting means therefor, comprising
- 20
- ing a fixed section and a movable section, one section resting on the other section, and the sections at the junction having overlapping flanges, a bearing joining the sections, a spring surrounding the bearing and connected to each section, a gear member extending laterally from the movable section, an object supporting means operable from the said gear member, a dog pivoted to the movable section, said gear member lying in the path of movement of the dog in one direction, and keeper means on the fixed section engageable by the dog.
- 25
- 30
- 35
- In testimony whereof, I have affixed my signature in the presence of two witnesses.
- EARL R. MOODY.
